FORM FOR SHAPING HOSIERY AND THE LIKE

Application filed July 9, 1928. Serial No. 291,368.

This invention relates to forms for shaping textile articles like hosiery, and more particularly to forms intended for use in connection with automatic finishing apparatus such as shown and described in our copending application, Serial No. 291,367, concurrently filed herewith. The process for the practice of which this apparatus is especially designed produces in stockings knit from silk or rayon (artificial silk), an improved high luster finish which is marked by a uniform sheen throughout. The attainment of such finish is dependent to a great extent upon maintenance of uniform tension upon the articles throughout the various stages of the process.

The present invention is directed toward the provision of a shaping form by which the foregoing desiderata may be realized in practice with assurance of a perfect finish whereby the appearance of the articles is greatly improved and their salability correspondingly enhanced.

In connection with a shaping form having the described attributes, we further aim to secure the advantages attendant upon simplified construction, and to provide lengthwise tension applying means capable of easy manipulation on the form incidental to attachment to and detachment from the articles with avoidance of grippage over a large area such as would be likely to impair the fabric or mar its finish.

Further objects and advantages of this invention will be manifest from the detailed description following of the typical embodiment illustrated in the drawings, wherein Fig. I is an elevation of our improved shaping form.

Fig. II is a plan section on a larger scale, taken as indicated by the arrows II-II in Fig. I.

Fig. III is a view similar to the immediately preceding illustration but on a still larger scale, taken as indicated by the arrows III-III in Fig. I.

Fig. IV shows an edge view of the lower portion of the form viewed in the direction of the arrows IV-IV in Fig. I.

Fig. V is a vertical detail sectional view, taken as indicated by the arrows V-V in Fig. I; and,

Fig. VI shows an alternative detail.

As herein shown, our improved shaping form comprises a light open metallic profile frame 10 which is preferably cast integral with its verticals 11 connected at the bottom by a sturdy cross bar 12, as well as at spaced intervals of its height by additional thinner cross bars 13—all contributing to the strength and rigidity of the structure as a whole. 55 From Fig. III it will be observed that the verticals 11 are substantially elliptic in cross-section, with the major axes of the ellipses lying in the medial plane of the form. As shown in Figs. II and III, the outer periphery of the form is made quite sharp to provide an effective scoring edge 14 and its rear vertical edge is continuously recessed along one side as at 15 to accommodate the central seam at the back of the stocking. Near its 60 lower end and at opposite sides, the form is equipped with rollers 16, which are arranged in horizontally associated pairs for engaging 65

fixed opposed channel rails 17 of the finishing machine with which the form is to be used. The described arrangement affords the form support and guidance in vertical position incidental to progression in the apparatus. At the region of attachment of the rollers 16, the spaced verticals 11 of the form are thickened and made to circular cross-section as at 18 for snug fitment in the interval between the opposing guide channel rails 17, 70 and to ease rounding of curves along the line of progression in the finishing apparatus. 75

A stem 19, depending centrally from the bottom cross bar 12 of the form, has projecting laterally from its lower end, as shown in Figs. I and V, a lug 20 to engage one of the interstices of a sprocket chain 21, whereby the 80 85 90 95

form is progressed along the guide rails 17.

For the purpose of inducing uniform lengthwise tension in the stocking stretched over the form (such stocking being partly shown at S in Figs. IV and V and in cross-section in Fig. II) we provide a "dead-weight" member 22 which is slideable vertically in that part of the opening in the frame 10 lying between the bottom cross bar 12 and the first of the intermediate or supplemental cross bars 13. This dead-weight member 22 is of rectangular plate-like configuration and somewhat thinner (Fig. III) than the frame verticals 11 with avoidance of lateral projection therebeyond and for capacity to be readily overlapped by the lower edge of the stocking S as the latter is drawn down over the form. Referring again to Fig. III and also to Fig. II, it will be noted the side edges of the member 22 are V grooved as at 23 to engage the tapered inner edges 24 of the frame verticals 11, said member being thus guided to true up-and-down movement in the opening of the frame 10 for the purpose indicated. The tension applying member 22 has a separable edge portion 22a secured by screws 25 to enable initial assembling in the frame 10. Pivoted at 26 to opposite faces of the tension applying member 22 are clamping jaws 27 which are fitted at their tops with contact bars 28 for engaging the stocking fabric. As shown in Figs. IV and V, these contact bars 28 are fashioned from stout round wire and have their ends turned laterally for projection through bosses 29 of the clamping jaws 27 and to take securing nuts 30. By virtue of this arrangement the tension applying member 22 is effectively clamped to the lower end of the stocking S, with preclusion of contact over a prohibitive area such as would be likely to mar the appearance of the texture of the finished article. The clamping jaws 27 are actuated in opposition to a spring 31 (which is common to them both and tends to move them to open position) by a lever 32. This lever 32 is pivoted at 33 to a clevised lug 35 projecting sidewise from the member 22, and has parallel fingers 36 with rounded ends adapted to co-operate with inclined cam surfaces 37 at the out sides of the clamp jaws 27. The lever 32 also has upwardly and downwardly extending extremities 38, 39 with lateral terminal lugs 38a, 39a adapted for individually fixed actuating cams (not shown) along the course of the form in the finishing apparatus. Projecting from opposite sides of the tension member 22, near its lower edges, are rollers 40, which, incidental to travel of the form through the finishing apparatus, run on parallel rails 41 lying along the prescribed course of travel of the form.

In the use of our invention, the stocking S is pulled down over the frame 10 of the form, which, as shown in Fig. I, may be provided on

its verticals 11 with transverse markings M, M for determining the level to which the edge about the opening of said stocking is to be drawn, proper placement during the operation being facilitated as a consequence of lodgement afforded the stocking seam within the recess 15. When thus mounted on the form, the stocking S may be readily inspected for imperfections or blemishes by virtue of visibility through the open frame 10. With the foregoing accomplished the tension applying member 22 is raised either by hand, or automatically by a rise in the rail 41 as in our co-pending application hereinbefore referred to, and the clamping jaws 27 closed in so that the stocking S is engaged at opposite sides directly above the edge around its opening, between the member 22 and the contact bars 28 of said jaws. Such actuation of the clamping jaws 27 is brought about by counter-clockwise swinging of the lever 32, likewise either manually or by automatic means such as disclosed in the application, supra. Upon release of the member 22 to drop under its own weight, the stocking S is obviously placed under lengthwise tension on the form, the extent of descent of the member 22 being, however, restricted through arrest of the rollers 40 by the rails 41. The function of tensioning the stocking S is thus vested solely in the weight of the member 22 and the parts thereto attached. This does not necessarily result in equal elongation of successive stockings S but the tension induced is nevertheless uniformly distributed in each.

In the alternative form of our invention shown in Fig. VI a pair of opposing channel rails 41a is employed (in lieu of the plain rails 41 of the first embodiment) for cooperation with the rollers 40 of the tension applying member 22. With the modified arrangement, the member 22 is always positively pulled downward without reliance on the weight of said member for the desired tensioning action. In this instance it will be seen that uniformly-distributed tension is induced through equal elongation of successive stockings S.

While we have herein shown in part, and also on occasion alluded to mechanical or automatic means for actuating the shaping form, our invention is not to be considered as limited in this respect since the tension applying member 22 may obviously be manipulated manually and the clamping jaws 27 likewise operated by hand in effecting attachment to the stocking.

Having thus described our invention, we claim:

1. A form for shaping textile articles, such as hosiery, comprising a profile frame, a dead-weight tension applying member guided in the frame without projection therebeyond, and means for clamping said weighted member to the article stretched on the frame.

2. A form for shaping textile articles, such as hosiery, comprising a profile frame, a dead-weight tension applying member slidably guided in the frame without projection therebeyond, and means for clamping said tension applying member to the article stretched on the form. 5
3. A form for shaping textile articles such as hosiery comprising an open profile frame, a dead-weight tension applying member slidably guided within an opening of the frame without projection therebeyond, and means for clamping said tension applying member to the article stretched on the form. 10
4. A form for shaping textile articles such as hosiery comprising a profile frame, a dead-weight tension applying member movable in the frame without projection therebeyond, and clamp means on said member for engaging the article stretched on the form. 15
5. A form for shaping hosiery and the like comprising an open profile frame, a dead-weight tension applying member guided to vertical movement in an opening of the frame through engagement of side grooves with spaced frame verticals without projection therebeyond, and associated means for clamping said member to the article stretched on the form. 20
6. A form for shaping textile articles, such as hosiery, comprising an open profile frame, a dead-weight tension applying member guided in the frame without projection therebeyond and adapted to be overlapped by the lower edge of the article incidental to drawing of the latter down over the form, and means for clamping said member to the article. 25
7. A form for shaping hosiery and the like, comprising an open profile frame, a dead-weight tension applying member vertically slidable in an opening of the frame with avoidance of lateral projection therebeyond for capacity to be overlapped by the lower edge of the article incidental to drawing of the latter down over the form, and means for clamping said member to the article. 30
8. A form for shaping hosiery and the like comprising an open profile frame, a dead-weight tension applying member vertically slidable in an opening of the frame with avoidance of lateral projection therebeyond for capacity to be overlapped by the lower edge of the article as the latter is drawn down over the form, opposing clamp jaws pivoted to opposite sides of said member, and means to concurrently actuate the jaws to clamp the article. 35
9. A form for shaping textile articles such as hosiery, comprising an open profile frame, a dead-weight tension applying member vertically slidable in an opening of the frame with avoidance of lateral projection there- 40
- beyond for capacity to be overlapped by the lower edge of the article as the latter is drawn down over the form, opposing clamp jaws pivoted to opposite sides of said member with springs tending to urge said jaws to open position, and means to concurrently close the clamp jaws in opposition to the influence of the springs. 45
10. A form for shaping textile articles such as hosiery comprising an open profile frame, a dead-weight tension applying member vertically slidable in an opening of the frame with avoidance of lateral projection therebeyond for capacity to be overlapped by the lower edge of the article as the latter is drawn down over the form, opposing clamp jaws pivoted to opposite sides of the member with springs tending to urge said jaws to open position, an actuating lever fulcrumed on said member having parallel fingers to cooperate with inclined cam surfaces on the jaws and thereby move them concurrently to closed position in opposition to the springs in clamping the member to the article. 50
11. A form for shaping textile articles such as hosiery adapted to be employed in connection with automatic finishing apparatus, said forms comprising an open profile frame cast integrally with spaced verticals of substantially elliptic cross-section with the rear edge continuously recessed and connected at intervals by cross bars, and a stem depending from the lowermost cross bar for engagement by the progressing means of said finishing apparatus. 55
12. A form for shaping textile articles such as hosiery and the like adapted for use in connection with automatic finishing machinery, said form comprising a profile frame with the verticals of substantially elliptic cross-section and the rear edge continuously recessed along one side, rollers arranged in spaced pairs at opposite sides of the form to engage opposing channel guides for support and guidance of the form in vertical position incidental to progression in said apparatus. 60
13. A form for shaping textile articles such as hosiery comprising an open profile frame constructed integrally with a cross bar connecting its verticals at the bottom, and a dead-weight tension applying member slidably in an opening of the form, said member having grooves in opposite side edges for engagement with spaced verticals of the form, and part of one edge portion being removable to enable assembling in the frame of the form. 65
14. A form for shaping textile articles, such as hosiery, comprising a profile frame, a dead-weight tension applying member slidably guided in the frame without projection therebeyond and adapted to be suspended from the lower end of the article stretched on said frame, and means for limiting the descent of said tension applying member. 70
15. A form for shaping textile articles, 75

such as hosiery, comprising a profile frame,
a dead-weight tension applying member slid-
ably guided for up-and-down movement in
the frame without projection therebeyond,
and means cooperating with said member to
control the amount of tension applied to the
article stretched on the form.

In testimony whereof, we have hereunto
signed our names at Lansdale, Pennsylvania,
this 29th day of June, 1928.
